E. A. Laboratories, Inc., Brooklyn, N. Y., a corporation of New York

Application March 8, 1949, Serial No. 1,266

Term of patent 14 years

(Cl. D81—10)

To all whom it may concern:

Be it known that I, Ray R. Hutcheson, a citizen of the United States, residing at Brooklyn, in the county of Kings and State of New York, having invented a new, original, and ornamental Design for a Combination Hair Drier and Heater, of which the following is a specification, reference being had to the accompanying drawing, forming a part thereof, wherein:

Fig. 1 is a top plan view of a combination hair drier and heater embodying my new design;

Fig. 2 is an elevational view of one side, thereof;

Fig. 3 is a front elevation; and

Fig. 4 is a view of the side opposite that shown in Fig. 2 on a reduced scale and with one end in raised position.

The essential features of my design reside in the portions shown in full lines.

I claim:

The ornamental design for a combination hair drier and heater, substantially as shown and described.

RAY R. HUTCHESON.
